RIDDLE

Vernon J. Davis, Buffalo, N. Y.

Application December 7, 1929, Serial No. 412,471

7 Claims. (Cl. 209—326)

This invention relates to improvements in riddles of the kind which, although available for other purposes, have characteristics which render them particularly desirable in connection with sand screening operations. A riddle of this type consists generally of a screen bearing frame which is operatively connected for vibratory movements to a suitable motor and an auxiliary mechanism which co-operates with the actuating mechanism in the support of the frame, the auxiliary mechanism, being designed to permit the vibratory movements of the said frame which are effected through the agency of the motor.

One object of the present invention is to provide an auxiliary supporting mechanism of the type generally described which, while capable of permitting relatively high speed vibration of the frame, is quiet in operation and in which wearing of the parts is minimized, thereby enabling its use over long periods without the necessity of adjustment or replacement of parts.

A further object is an auxiliary supporting mechanism which is adjustable thereby facilitating rapid assembly of the parts as well as enabling compensation for wear.

A further object is to provide an improved construction of screen bearing unit for a riddle of the type in which the operating and supporting mechanisms are located wholly beyond one end of the riddle, thereby enabling use of the riddle in a limited space as, for example, between the discharge end of a sand hopper and a chain of molds therebeneath, it being advantageous in order to save time and labor to screen the sand during its passage from the sand hopper to the molds.

A further object is to provide an improved actuating mechanism by which the screen is subjected to relatively high speed vibrations of a relatively short throw best adapted to the passage of a maximum quantity of material through the riddle in a given period of time.

A still further object is to provide an improved screen so constructed as to insure a substantially uniform distribution of the sand or material therein over the greater portion of the screening surface during the vibratory movements of the riddle, this object contemplating the provision of a series of corrugations presenting inclined faces to the normal outward flow of the material and tending to counteract such flow.

The invention is illustrated in the accompanying drawings in which:

Figure 1 is a side elevation of the riddle and operating mechanism therefor.

Figure 2 is a plan view of the same.

Figure 3 is a fragmentary view partially in section showing the eccentric mounting of one of the arms of the vibrating unit upon one end of the motor shaft.

Figure 4 is a section along line 4—4 of Figure 2 with the motor in elevation.

Figure 5 is a section along line 5—5 of Figure 2; Figure 6 is a section along line 6—6 of Figure 5.

Figure 7 is a section along line 7—7 of Figure 5.

The invention is illustrated in connection with a riddle of the type described in my Patent No. 1,728,335 of September 17, 1929, in which the operating and supporting mechanisms for the screen bearing frame are located wholly beyond one end of the frame. It is to be understood, however, that insofar as the auxiliary supporting mechanism herein described and claimed is concerned the invention is not dependent upon the location or construction of the operating and supporting mechanisms, the riddle shown and described being solely for the purpose of illustration.

The screen box 1, as illustrated, is supported for vibratory movement by a horizontal unit 2 which is carried by a suitable support, the vibrating unit and support therefor extending wholly beyond one end of the screen box. The support is preferably mounted for swinging movement in a horizontal plane to permit the riddle to be swung to one side when not in use. It includes a fixed bracket 3 and a swinging member 4, the two said parts being pivotally connected by a pivot pin 5. The swinging member 4 is adapted to carry the riddle supporting and actuating mechanism and, as illustrated, is beam-like in form. It is provided at its outer end with a vertical supporting plate 6 to which is secured, as at 6a, a suitable electric motor 7, which is adapted to move the unit 2 and the riddle carried thereby in a substantially elliptic path.

The vibrating unit comprises angularly extending arms 14 which are joined at their inner ends and which diverge from such jointure to straddle the motor 7. They extend beyond the motor to provide means for supporting the screen box 1. The shaft 8 of the motor is operatively connected to the arms 14 to vibrate the unit. For this purpose, the shaft 8 is extended at each end as at 9, which extensions carry balance wheels 10 fixed thereto. The hubs of the balance wheels are fashioned to provide eccentrics 12 which are journaled in suitable ball bearings 13 mounted in openings 14a formed in the arms 14. The said openings 14a co-operate with suitable plates 15 and 16 to delimit lubricating chambers which may be sealed by suitable packing 15a and within which the ball bearings 13 are housed.

The inner end of the vibrating unit is connected to the swinging member 4 to permit the movement of the unit in the manner described. The web portion of the member is, therefore, cut away to provide an opening 4a in which the said end is supported, the opening, of course, being large enough to permit the vibratory movement

of the unit. The said end is adapted to be supported in the opening 4a between opposed bosses 17 and 18 preferably formed integral with the upper and lower chords respectively of the beam 5 and disposed centrally of the opening 4a. The upper and lower bosses are provided upon their opposing faces with recesses 17a and 18a respectively. A disc 19 is seated in the lower recess 18a and a disc 20 is adjustably seated in the recess 10 17a. The disc 19 is preferably resiliently seated and for this purpose any suitable means may be employed, such means being illustrated as comprising a resilient disc 20a of rubber or the like which normally urges the disc 19 upwardly to 15 maintain engaging co-operation between the supporting elements of the inner end of the vibrating unit at all times during its operation whether the unit be in its extreme outward position or whether in a position intermediate its 20 extreme outward and inward positions.

A fulcrum 21 is adapted to support the pivoted end of the unit and is mounted in a recess in the disc 19 or may be integral therewith. In substantially vertical alignment with the fulcrum 25 21 are upper and lower bushings 23 and 24 which are preferably removably clamped between the inner ends of the angular extending arms 14 of the vibrating unit. As best illustrated in Fig. 5, the upper bushing 23 is provided with a fulcrum 30 25 similar to the fulcrum 21 in the lower disc while the lower bushing 24 has a V-shaped recess 26 similar to the recess 22 in the upper disc 20. Two similar elements 27 and 28, each having its upper pointed end positioned in a companion recess and its lower inverted V-shaped end seated upon a companion fulcrum are adapted to suitably space the inner end of the unit in the opening 4a, the recesses co-operating with the upper 30 35 ends of the spacing elements to prevent lateral movement of the same, it being understood, of course, that the vibrating movement of the unit effected by the eccentrics on the motor shaft is not sufficient to dislodge the elements from the said recesses and that the elements are maintained in assembled co-operative relation by the 40 45 connection of the vibrating unit with the motor.

In order to compensate for wear and to permit substitution of new parts for worn ones, the upper disc 20 is adapted to be adjusted vertically 50 in the recess 17a. An adjusting screw 120a is, therefore, provided in the upper boss 17 which may be rotated to increase or decrease, to the desired extent, the pressure under which the supporting elements 27 and 28 function.

From the foregoing it will be apparent that the screen bearing unit is partially supported by the actuating mechanism which includes the motor 7 and partially by the elements 27 and 28. For convenience the mechanism which includes 55 60 these two elements has been referred to as the auxiliary supporting mechanism. In the embodiment of the invention illustrated the greater part of the load is carried by the actuating mechanism. The term "auxiliary", however, is not necessarily intended to indicate that the auxiliary supporting mechanism carries a smaller part of the load than the actuating mechanism. It will be understood, of course, that this will not be the case in those instances where the auxiliary supporting mechanism is employed in connection with a riddle in which the actuating mechanism may be supported upon the opposite side of the screen box from that illustrated.

During vibratory movements of the unit 2 the 70 75 screen box 1 is moved through a substantially

elliptic path. Lengthwise movement of the unit 2 during such vibration is relatively small and this results in slight rocking movements of the elements 27 and 28. The elements are so formed at their ends that their engagement with the members 19 and 20 carried by the swinging member 4 as well as their engagement with the bushings 23 and 24 carried by the unit 2 is effected through the agency of "knife edges". Such a construction has the advantage that wearing of the parts during vibration of the screen bearing frame is minimized, thereby insuring quiet operation over long periods of use without the necessity of adjustment or replacement of parts. The resilient disk beneath the disk 19 maintains the various parts of the auxiliary supporting mechanism in tight alignment and renders frequent adjusting unnecessary in addition to insuring quiet operation of the parts.

The balance wheels 10 may be counterbalanced as at 10a in order to relieve the shaft 8 from strain during the screening operation. It will be noted that the overbalanced portion of the wheel is diametrically opposite the thickest portion of the eccentric formed upon the hub extension. By virtue of this arrangement, the overbalanced portion of the wheel is always at the top when the vibrating unit and screen carried thereby are in their lowest vertical position and vice versa, whereby the said balance wheel always tends to counteract the action of the vibrating unit upon the motor shaft.

The screen box 1, as stated, is supported for vibration between the arms 14. It, therefore, carries trunnions 30 which are journaled in 35 bearings 31 provided at the outer ends of the said arms. Rubber bushings 30a may be utilized to insure a tight fit between the parts of the bearing assembly and to prevent rattling of the said parts during the vibration of the box. The box is maintained against rotation in a normally horizontal position by laterally extending lugs 32 carried by the arms 14 and a latch 33, the said lugs engaging the rear lower corners of the screen box and the latch 33 extending over and 40 45 engaging the upper edge of the back of the screen box intermediate its sides. The latch 33 is illustrated in its normal operative position in which it extends over the upper edge of the screen box as described but it may be withdrawn by operating the handle 33a which is pivotally mounted in a housing 34. The housing 34 is supported in co-operative relation with respect to the screen box by a transverse tie-bar 35 which is secured at its opposite ends to the arms 14 and cut away as at 35a (Fig. 3) to permit the vibratory movement of the unit 2, the motor, of course, being stationary during this movement. In addition to providing a support for the latch housing the bar 50 55 60 65 70 75 80 85 90 95 35 also functions as a brace to keep the arms 34 properly spaced. When it is desired to clean the screen the latch 33 may be withdrawn into the housing 34 in the manner described and the screen box rotated in a clockwise direction to an upside down position. When the accumulated matter has been discharged the screen is returned to its original position by rotating it in an anti-clockwise direction until the rear lower corners of the screen box engage the lugs 32 at which time the handle 33a may be released to permit the latch 33 to be extended over the upper edge of the back of the screen box.

It will be observed that during the operation of the actuating mechanism, the motor shaft rotating in the direction of the arrow (Fig. 3), the

- outer end of the unit and the riddle carried thereby are vibrated in a substantially elliptical path. Inasmuch as the spacing elements 27 and 28 maintain the inner end of the vibrating unit in 5 substantially the same horizontal plane during this movement of the outer end of the unit, the riddle will be progressively canted in fore and aft directions during its opposite vertical vibrations. These vertical movements of the riddle in its path 10 of vibration are more rapid than the fall of the sand. Consequently the screening fabric will strike the sand with such force as to tend to break the lumps and cause them to rebound, this action being aided by the canting of the riddle as 15 described. The canting action of the riddle also aids in obtaining a fore and aft shifting of the mass of sand relatively to the screening fabric so as to secure rapid and effective screening results.
- 20 During the vibratory movements of the screen the sand or other material therein normally tends to move toward the forward end of the screen and accumulates there while the rear portion of the screen is utilized only to a small extent. In order 25 to obtain a substantially uniform distribution of the material over the screening surface the screen is preferably formed with a series of transverse corrugations presenting inclined faces 36 toward the outwardly moving material, the extent of inclination of such faces being sufficient to counteract the normal tendency of the material to move to the outer end of the screen.
- It is apparent from the foregoing that the screen 30 may be operated and supported by mechanism located wholly beyond one end thereof if desired and that the space above and below said screen in this case is entirely unobstructed thereby permitting the screen to be moved to a position between a hopper and a chain of molds without being 35 obstructed by any part of the said hopper or molds and in such position rapidly vibrated for the purpose of screening the sand as it is delivered from the hopper and in the course of its 40 passage to the molds.
- 45 Having fully described my invention, I claim:
1. In a riddle the combination of a screen-bearing unit, a motor, a support for said motor, means for operatively connecting the motor to said unit for vibrating it and mechanism for connecting one end of said unit to said support, said mechanism being adapted to permit vibration of said unit by said motor and including opposed, inflexible, independently movable spacing elements which engage opposite sides of said unit 50 at said end, said elements preventing movement of said end in a direction transverse of the length of said unit while permitting lengthwise and pivotal movements of said end.
  2. In a riddle the combination of a screen-bearing unit, a motor, a support for said motor, means for operatively connecting the motor to said unit for vibrating it and mechanism for connecting one end of said unit to said support, said mechanism being adapted to permit vibration of said unit by said motor and including opposed independently movable spacing bars which engage opposite sides of said unit at said end, said bars preventing movement of said end in a direction transverse of the length of said unit while permitting lengthwise and pivotal movements of said end.
  3. In a riddle the combination of a screen-bearing unit, a motor, a support for said motor, means for operatively connecting the motor to said unit for vibrating it and mechanism for connecting one end of said unit to said support, said mechanism being adapted to permit vibration of said unit by said motor and including opposed, inflexible, independently movable spacing elements which engage opposite sides of said unit at said end, each of said bars have a pointed end and a recessed end which cooperate with companion recessed and pointed members, said bars preventing movement of the end of said unit in a direction transverse of its length while permitting lengthwise and pivotal movements of said end.
  4. In a riddle the combination of a screen-bearing unit, a motor, a support for said motor, eccentric carried by the shaft of said motor which are journaled in said unit, whereby said unit may be vibrated by said motor and mechanism for connecting one end of said unit to said support, said mechanism being adapted to permit vibration of said unit by said motor and including opposed, inflexible, independently movable spacing elements which engage opposite sides of said unit at said end, said elements preventing movement of said end in a direction transverse of the length of said unit while permitting lengthwise and pivotal movements of said end.
  5. In a riddle the combination of a screen-bearing unit, a motor, a support for said motor, means for operatively connecting the motor to said unit for vibrating it, mechanism for connecting one end of said unit to said support, said mechanism being adapted to permit vibration of said unit by said motor and including opposed, inflexible, independently movable spacing elements which engage opposite sides of said unit at said end, said elements preventing movement of said end in a direction transverse of the length of said unit while permitting lengthwise and pivotal movements of said end and means carried by said support for cooperating with one of said elements, said means being adjustable to maintain the desired adjustment of said elements.
  6. In a riddle the combination of a screen-bearing unit, a motor, a support for said motor, means for operatively connecting the motor to said unit for vibrating it, mechanism for connecting one end of said unit to said support, said mechanism being adapted to permit vibration of said unit by said motor and including opposed, independently movable spacing bars which engage opposite sides of said unit at said end, said bars preventing movement of said end in a direction transverse of the length of said unit while permitting lengthwise and pivotal movements of said end, a member carried by said unit and against which one of said bars bears and means for resiliently supporting said member.
  7. In a riddle the combination of a screen-bearing unit, a motor, a support for said motor, means for operatively connecting the motor to said unit for vibrating it, mechanism for connecting one end of said unit to said support, said mechanism being adapted to permit vibration of said unit by said motor and including opposed, independently movable spacing bars which engage opposite sides of said unit at said end, said bars preventing movement of said end in a direction transverse of the length of said unit while permitting lengthwise and pivotal movements of said end, members carried by said support against which the said bars bear, means for resiliently mounting one of said members and means for adjustably mounting the other of said member, whereby the desired adjustment between said bars can be maintained.
